UNITED STATES PATENT OFFICE

2,195,247

RAILWAY CAR VESTIBULE DIAPHRAGM

Hugh H. Hendrickson, Elkhart, Ind., assignor to
 The Adlake Company, Chicago, Ill., a corpora-
 tion of Illinois

Application August 5, 1936, Serial No. 94,355

3 Claims. (Cl. 105—15)

This invention has to do with diaphragms of the type used in connecting together the adjoining ends of railway cars, and is particularly concerned with the provision of a diaphragm suitable for articulated streamlined trains.

The object of the invention is to provide an improved diaphragm of novel construction which will bridge the sides and tops of the ends of adjoining cars substantially flush with the outer surfaces of the same without allowing the entry of dust, cinders, rain and air currents and without having the continuity of the connection disturbed in any way by the turning movement of the cars.

Other more specific objects and advantages of the invention will be apparent to those skilled in the art upon a full understanding of the construction, arrangement and operation of the parts constituting the new diaphragm.

A preferred form of the invention is presented herein by way of illustration, but it will of course be appreciated that the invention is susceptible of embodiment in other structurally modified forms coming equally within the scope of the appended claims.

In the accompanying drawing:

Fig. 1 is a fragmentary side view of the ends of adjoining cars, showing the new diaphragm in position;

Fig. 2 is a top view of the same, with portions at the sides shown in horizontal section; and

Fig. 3 is a vertical section, taken on the line 3—3 of Fig. 1.

The drawing shows the ends of two adjoining cars 10 connected by the new diaphragm 11. The diaphragm and the ends of the cars are all U-shaped in transverse section and the diaphragm is of substantially the same size as the ends of the cars and is disposed practically flush with the outer surfaces of the latter. The diaphragm is flexible and is preferably made of heavy woven belting material, although it may of course be made of any other suitable material.

The diaphragm is longer than the space between the ends of the cars and the edges of the diaphragm extend into pockets 12 which are provided about the outer edges of the ends of the cars. These pockets are closed on the inside by plates 13 and on the outside by plates 14, which latter plates may form a part of the outer sheathing of the car but are preferably made separate so as to permit of their removal. The ends of the pockets 12 are closed by cross plates 15 and the openings to the pockets through which the edges of the diaphragm extend are partially

closed by outwardly directed flanges 16 even with the ends 17 of the cars, which flanges are rounded at their edges for substantially frictionless engagement with the inside surface of the diaphragm. The flanges 16 are of such extent as to leave narrow slots 18 which are but little wider than the thickness of the material of the diaphragm.

The edges 19 of the diaphragm within the pockets 12 are connected to coil springs 20, which coil springs are in turn connected under tension to the cross plates 15. The springs 20 are arranged at regularly spaced intervals along the edges of the diaphragm, across the top and down both sides, and the ends of the springs which are connected to the cross plates 15 are offset inwardly with respect to the edges 16 of the flanges so that the springs 20 will not only maintain the diaphragm taut at all times but will also maintain the same in snug engagement with the edges of the flanges 16. This engagement of the diaphragm with the flanges 16 will prevent the entry of foreign matter into the space between the ends of the cars, and the smoothness of the edges of the flanges will allow the diaphragm to slide back and forth with respect to such edges during the turning movement of the cars without appreciable wear. Any foreign matter entering the narrow slots 18 opening into the pockets 12 about the outside of the diaphragm will be discharged through suitable openings in the bottoms of the pockets.

By this construction the continuity of the tops and sides of adjoining cars in streamlined trains can be preserved without difficulty, the tensioned springs 20 serving to keep the diaphragm taut regardless of the relative positions of the cars, and the depth of the pockets and the extent of projection of the edges of the diaphragm thereinto being sufficient to take care of the diaphragm in all angular positions assumed by the cars.

I claim:

1. The combination with two railway cars provided with confronting pockets of inverted U-shape about the top and side edges of the adjacent ends of the cars, which pockets extend about the top and side edges of said ends, of a flexible diaphragm of inverted U-shape extending from one car to the other with the edges of the diaphragm conforming to and positioned in the pockets, flanges on the ends of the cars at the inner edges of the pockets, and springs in the pockets attached to the edges of the diaphragm for holding the diaphragm against the flanges.

and for maintaining the diaphragm taut in all angular positions assumed by the cars.

2. The combination with two railway cars provided with confronting pockets of inverted U-shape about the top and side edges of the adjacent ends of the cars, which pockets extend about the top and side edges of said ends, of a flexible diaphragm of inverted U-shape extending from one car to the other with the edges of the diaphragm conforming to and positioned in the pockets, flanges on the ends of the cars at the inner edges of the pockets, and springs in the pockets attached to the edges of the diaphragm for holding the diaphragm against the flanges and for maintaining the diaphragm taut in all angular positions assumed by the cars, each of said springs being disposed at right angles to the edge of the diaphragm in a plane which is tilted slightly with respect to the plane of the portion of the diaphragm spanning the flanges opposite the spring.

3. The combination with two railway cars provided with confronting pockets of inverted U-shape about the top and side edges of the adjacent ends of the cars, which pockets extend about the top and side edges of said ends, of a flexible diaphragm of inverted U-shape extending from one car to the other with the edges of the diaphragm conforming to and positioned in the pockets, flanges on the ends of the cars at one of the side edges of the pockets, and springs in the pockets attached to the edges of the diaphragm for pressing the diaphragm resiliently against the flanges and for maintaining the diaphragm taut in all angular positions assumed by the cars, each of said springs being tilted slightly with respect to the plane of the portion of the diaphragm spanning the flanges opposite the spring, whereby to press the diaphragm resiliently against the flanges into sealed engagement with the latter.

HUGH H. HENDRICKSON.
